UNITED STATES PATENT OFFICE

WILLIAM H. GREELEY, OF NEWTON, MASSACHUSETTS, ASSIGNOR TO GINN AND COMPANY, OF BOSTON, MASSACHUSETTS, A COPARTNERSHIP

BOOKHOLDER

Application filed December 16, 1929. Serial No. 414,608.

The present invention relates to book holders particularly adapted for holding books in open position as for purposes of display or to permit copying.

5 The object of the present invention is to provide a book holder adapted to maintain in open position a book of substantially any size and having covers of any thickness. To this end, the present invention comprises the 10 book holder hereinafter described and particularly defined in the claim.

In the accompanying drawings, Fig. 1 is a plan view of the preferred form a holder and Fig. 2 is perspective view of a book 15 held in open position by the holder.

The illustrative embodiment of the invention comprises a wire of resilient material formed in the shape shown in Fig. 1. The holder has a center bar 4 together with two 20 resilient clip portions 6 formed perpendicular thereto at the ends. Each clip portion 6 comprises a straight length of wire 8 and a curved length 10 immediately adjacent thereto. The lengths 8 and 10 are separated by 25 a considerable distance at the lower end of the clip and are brought into close converging relationship at the open end. Each extreme end of the wire is formed with a loop 12 to form a smooth end and protect against 30 catching or tearing of the material of the book.

In use, the book 14 is supported as shown in Fig. 2, the loops 6 engaging with the covers. Upon engagement with a cover, the 35 converging portions of the clip tend to spread into substantially parallel relationship, thus gripping the cover over a considerable surface. The invention has the advantage that by virtue of the enlarged bottom portion of 40 each loop, covers of a considerable thickness may be accommodated, whereas by the restricted space afforded by the upper end of the loop, sufficient resiliency is afforded to hold the thinnest covers as firmly as is necessary. The holder is therefore adapted for 45 general application to book covers of a considerable thickness.

Having described the invention, what I claim is:

50 A book cover holder comprising a piece

of wire formed with a center bar, and two resilient clips only, each formed perpendicularly to the center bar at the ends thereof, each clip consisting of two adjacent lengths of the wire separated from each other at 55 the bottom by a sufficient distance to accommodate covers of a considerable thickness and having portions closely adjacent to each other and converging together at the open end to resiliently grip the covers, the two 60 clips lying in the same plane and including the center bar.

In testimony whereof I have signed my name to this specification.

CERTIFICATE OF CORRECTION.

Patent No. 1,811,124.

Granted June 23, 1931.

It is hereby certified that the name of the inventor in the above numbered patent was erroneously written and printed as "William H. Greeley", whereas said name should have been written and printed as Willian H. Greeley, as shown by the records in this office; page 1, line 13, for the article "a" second occurrence read of; line 14, after the word "is" insert the article a, and line 16, for the word "illustrative" read illustrated; and that the said Letters Patent should be read with these corrections therein that the same may conform to the record of the case in the Patent Office.

Signed and sealed this 4th day of August, A. D. 1931.

(Seal)

Wm. A. Kinnan,
Acting Commissioner of Patents.
